(57) **CLAIM**

The ornamental design for a “housing”, as shown and described.

DESCRIPTION

FIG. 1 is a top, front, and right side perspective view of a housing showing our new design, the broken-line disclosure of a rotary window crank, and window frame fragments being for illustrative purposes only and forming no part of the claimed design;

FIG. 2 is an enlarged front elevational view thereof;

FIG. 3 is an enlarged left side elevational view thereof;

FIG. 4 is an enlarged left side elevational view thereof; and,

FIG. 5 is an enlarged top plan view thereof.

The broken-line disclosure of internal elements in the last three figures is also for illustrative purposes only and forms no part of the claimed design.
